UNITED STATES PATENT OFFICE.

MARTIN ANDREW WINSTEAD, JOHN DUNHAM REID, AND WILLIAM CASSIUS MOODY,
OF LUNDELL, ARKANSAS.

ANTICHOKE ROLL AGITATOR.

Application filed April 19, 1927. Serial No. 185,012.

The present invention relates to an agitator and has for its object to provide means which will assist the roll in a cotton gin in turning so as to give the roll an even turn from end to end. As is well known the roll without an agitator gives much trouble, sometimes stopping in the center or at either end.

Another important object of the invention is to provide a structure of this nature which is efficient and reliable in its operation for imparting uniform movement to the roll so as to prevent the gin saws from cutting the cotton fiber which is so frequently the cause of the ruination of the staple of the cotton.

A still further important object of the invention lies in the provision of a structure of this nature which is simple in its construction, inexpensive to manufacture, easy to install, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

30 In the drawing:

Figure 1 is a fragmentary front elevation of a roll box with a portion of the front taken away to show the interior mechanism including the novel features of this invention,

Figure 2 is a transverse vertical section therethrough,

Figure 3 is an end elevation thereof,

Figure 4 is an enlarged detail section showing the spider, the head, and the shaft associated together,

Figure 5 is a perspective view of the shaft, and

Figure 6 is a sectional view through the shaft showing one of the cross rods in elevation.

Referring to the drawing in detail, it will be seen that the numeral 5 denotes the roll box having journalled therein a shaft 6 on which is disposed a plurality of gin saws 7 of conventional or any preferred construction. These saws 7, of course, are disposed

in spaced relation as is clearly indicated in Figure 1. The sides of the roll box 5 above the saws 7 are formed with openings 8 and spiders 9 are formed on the outside of the sides of the box 5 to cross the openings 8. A shaft 10 is journalled in the spiders 9 and has collars 11 fixed thereto, one adjacent each spider 9. This shaft 10 is formed with a plurality of spaced openings 12 alternately arranged at right angles to each other. These openings 12 receive rods 13 the center portions of which are anchored in the openings 12 by means of set screws 14. These rods 13 are sufficiently long to move between the upper portions of the gin saws 7 when the shaft 10 is rotated as is clearly indicated in Fig. 2. The shaft 10 rotates in an opposite direction from the shaft 6 as is indicated clearly by the arrows in Figure 2. A pair of heads 15 are disposed on the shaft 10 for closing the openings 8. The shaft 10 is rotated at one-fifth the speed of the shaft 6 in any suitable manner such as through pulleys 16 and 17 operatively connected together by a belt 18. The pulley 16 is mounted on the shaft 10 at an end thereof exteriorly of the roll box 5 while the pulley 17 is mounted on a shaft 19 journalled in brackets 20.

This attachment efficiently prevents the roll from stopping and keeps it uniform from one end to the other. The attachment also lessens the strain on the saws and prevents the saws from cutting the cotton. As is well known when cotton is being ginned, and the roll becomes too tight and chokes and does not turn, the gin saws passing through the choke roll cuts the cotton fiber and ruins the staple of the cotton. This attachment effectively prevents this because it assists the roll in turning and thereby prevents the same from becoming choked.

It is thought that the construction, operation, utility, and advantages of this invention will now be quite apparent to those skilled in this art without a more detailed description thereof. The present embodiment of the invention has been disclosed in detail merely by way of example since in actual practice it attains the features of advantage enumerated as desirable in the statement of the invention and the above

description. It will be apparent that changes in the details of construction, and in the combination and arrangement of parts may be resorted to without departing from the spirit or scope of the invention as herein-after claimed or sacrificing any of its advantages.

Having thus described our invention, what we claim as new is:

- 10 1. In a cotton gin, a roll box, a shaft journalled in the roll box, gin saws on the shaft, the sides of said roll box being provided with openings and formed with exterior spiders crossing the openings, a second shaft journalled in the spiders to extend in parallelism with the first shaft, heads on the second shaft to close the openings, said second shaft provided with a plurality of transverse openings arranged in alternate right angular relation, rods extending through the openings, means for fixing the centers of the rods in the openings, said rods being sufficiently long to swing between the gin saws.

2. In a cotton gin, a roll box, a shaft 25 journalled in the roll box, gin saws on the shaft, the sides of said roll box being provided with openings and formed with exterior spiders crossing the openings, a second shaft, journalled in the spiders to extend in parallelism with the first shaft, heads on the second shaft to close the openings, said second shaft provided with a plurality of transverse openings arranged in alternate right angular relation, rods 35 extending through the openings, means for fixing the centers of the rods in the openings, said rods being sufficiently long to swing between the gin saws, collars on the second shaft, one adjacent each spider for preventing end play of said second shaft, and means for rotating the shafts in opposite directions.

In testimony whereof we have affixed our signatures.

MARTIN ANDREW WINSTEAD.
JOHN DUNHAM REID.
WILLIAM CASSIUS MOODY.
